(57) **CLAIM**

The ornamental design for a shoe, as shown and described.

DESCRIPTION

FIG. 1 is a front bottom perspective view of a shoe showing my new design;

FIG. 2 is a bottom view thereof; and,

FIG. 3 is a rear bottom perspective view thereof.
The broken lines depicting the remainder of the shoe show features that form no part of the claimed design.**1 Claim, 3 Drawing Sheets**(56)
